UNITED STATES PATENT OFFICE.

JOHN L. BRAGDON, OF CHICAGO, ILLINOIS.

CURTAIN-STRETCHER.

No. 884,999.

Specification of Letters Patent.

Patented April 14, 1908.

Application filed June 22, 1907. Serial No. 380,237.

To all whom it may concern:

Be it known that I, JOHN L. BRAGDON, a citizen of the United States, residing at Chicago, county of Cook, and State of Illinois, 5 have invented certain new and useful Improvements in Curtain-Stretchers, of which the following is a specification.

My invention relates to stretchers and driers for fabrics such as lace curtains or the 10 like.

The objects of my invention are, to provide an adjustable stretcher for lace curtains, which shall be of such improved construction as to occupy a minimum amount of 15 space when in use; to provide a stretcher which may be readily, quickly and accurately adjusted to any desired size by one person; and to provide a stretcher as mentioned which may be moved from one place 20 to another when in use without danger of tearing the curtains stretched thereon, or getting them out of shape.

A further object is to provide a stretcher as mentioned which shall be of a "knock-down" type, to the end that the same may 25 be packed flat for shipping, or to occupy but little space when not in use.

With these objects in view, my invention 30 is embodied in a stretcher comprising a suitably mounted drum formed of two end members longitudinally adjustable, but rotatably fixed in relation to each other, and means upon the drum for attaching the curtains thereto.

35 Further, my invention consists in a drum detachably secured to its axle and a suitable support therefor.

Further, my invention consists in an adjustable drum as mentioned in combination 40 with an adjustable support and means for securing the support in adjusted position.

My invention further consists in a drum formed of end members adjustable toward or 45 from each other and suitable longitudinal members adjustably secured thereto for receiving and holding the end of the curtains.

Further, my invention consists in various details of construction and arrangements of parts, all as will be hereinafter fully 50 described and particularly pointed out in the claims.

My invention will be more readily understood by reference to the accompanying drawing forming a part of this specification 55 and in which,

Figure 1 is a perspective view of a curtain

stretcher embodying my invention, Fig. 2 is a detail view, upon an enlarged scale, of a longitudinal member, Fig. 3 is a detail view of one of the longitudinal members for holding the ends of the curtains and illustrating a modified form thereof, and Fig. 4 is a cross section on the line, 4-4 of Fig. 3, the same being shown upon an enlarged scale.

My invention in its preferred form comprises an adjustable drum mounted upon an adjustable axle and supported upon an adjustable frame. The drum comprises a pair of end members, 1-1'. These are preferably circular, and each takes the form of a wheel having the usual spokes, 2, and hub, 3. The end members, 1-1', of the drum are mounted upon a suitable axle which projects a short distance beyond said members at each end of the drum to form gudgeons, 4, by 75 which the drum is rotatably supported upon the frame. The axle may be a plain rod, upon which the end members may be adjustably fixed, but I prefer the construction shown in the drawings.

As shown, I provide a two part shaft, and secure one of the end members to each, and form the parts of said shaft so that they telescope one within the other. To this end I provide a tubular shaft portion, 5, to which 85 the end member, 1 is secured, and a shaft portion, 6, of smaller diameter to telescope therein, and to which the member, 1' is attached. The end members of the drum may be permanently fixed to their respective 90 shaft portions but I prefer to have them detachable in order that the device may be taken apart and packed flat for shipping. When the end members are placed upon the shaft, they are rigidly and rotatably fixed 95 thereon by a key, 7, and a thumb screw, 8. The members, 1-1' are provided with a plurality of pins 9 arranged about the peripheries and upon which the edges of the curtain are secured.

100 It is obvious that as the shaft, 5-6, is telescopic, the members, 1-1', may be adjusted toward or from each other to accommodate curtains of any width. To prevent relative rotation of the members with consequent misshaping of the curtains, I provide a pin, 10, upon the member, 6, which engages a slot, 11, in the tubular shaft portion, 5. The supporting frame comprises a pair of uprights, 12, 12 arranged upon feet, 13 and a 110 cross or tie member, 14. The tops of the members, 12 are provided with recesses, 15,

to receive the gudgeons, 4 of the drum and the recesses, 15, are open at the top in order that the drum may be readily lifted from the frame. The tie rod, 14, is adjustably secured to the side members or uprights, 12, as at 16. The frame may be adjusted to accommodate the drum when the latter is adjusted to any width.

17—17 indicate bars detachably fixed to the peripheries of the members, 1—1'. These are provided throughout their length with pins, 18 adapted to receive and hold the ends of the curtains. These bars are secured upon the peripheries by clamps, 19, hence may be placed upon the end members in any position in order to accommodate curtains of any length.

In using the stretcher one of the bars, 17, is secured to the peripheries of the end members, and parallel with the shaft, and one end of the curtain is fixed upon the pins, 18. The drum is then rotated a little at a time and the edges of the curtain are secured upon the pins, 9. When the curtain is on the stretcher throughout its length, the other bar, 17 is clamped in proper position and the end of the curtain secured thereto. To prevent backward movement of the drum as the curtain is fixed thereon, I provide a ratchet device, 20. The fact that the bars, 17, project beyond the members, 1—1' when the device is adjusted for narrow curtains, does not interfere with the proper operation of the stretcher, as the circumference of the drum is greater than the length of the curtain to be stretched, therefore, the bars, 17 do not have to pass the standards, 12, when fastening a curtain upon the stretcher. However, if desired, the bars, 17, may be made adjustable in length, and in Fig. 3, I have shown such a bar. As illustrated in said figure the bar comprises the members, 17^a and 17^b.

Upon the inner end of each of said members, I secure a hoop, 21, which surrounds both members, and in one of said hoops, I provide a thumb nut, 22, which impinges against the member which slides therethrough. The members, 17^a and 17^b are equipped with pins, 18 throughout their length, and the member, 17^b is provided with a slot, 18^a, to accommodate the pins on the member, 17^a, when the members overlap to any extent.

55 To prevent sagging of the members, 1—1' due to the strain of the curtain stretched thereon, with the consequent unevenness of the curtain when dried, I provide a bar, 23. This is preferably fixed to the end members 60 by thumb nuts, 24, and the component parts thereof are adjustably secured to each other by a thumb nut, 25. This bar is similar in every respect to the adjustable bar, 17^a—17^b except that it is not provided with pins, and 65 is attached to the inner face of the members,

1—1' instead of the outer face thereof, in order to avoid contact with the curtains. Both the bars, 17 and 23 may be provided with a measuring scale as shown whereby the device may be accurately fixed to any 70 desired size.

Having described my invention, what I claim as new and desire to secure by Letters Patent is,

1. In a device of the class described a 75 shaft, a rotary drum mounted upon said shaft and comprising end members longitudinally adjustable and rotatably fixed in relation to each other, a plurality of pins in the peripheries of said members, and a plurality 80 of longitudinal bars adjustably secured to said end members, and a suitable support, substantially as described.

2. In a device of the class described, a 85 shaft, a rotary drum mounted upon said shaft and comprising end members longitudinally adjustable and rotatably fixed in relation to each other, a plurality of pins in the peripheries of said members, a pair of longitudinal bars adapted to be secured to said 90 end members, a plurality of pins on said bars, a longitudinally adjustable bar detachably secured to said members, and a suitable support, substantially as described.

3. In a device of the class described, a 95 supporting frame in combination with a two part telescoping shaft mounted in said frame, and a drum mounted on said shaft, said drum comprising a pair of end members having a plurality of pins in their peripheries, substan- 100 tially as described.

4. In a device of the class described, a supporting frame and a two part telescoping shaft, in combination with a drum, said drum comprising end members fixed upon respective parts of said shaft and having pins in their peripheries, and means for rigidly holding said end members against relative movement, substantially as described. 105

5. In a device of the class described, a sup- 110 porting frame and a two part telescoping shaft, in combination with a drum, said drum comprising end members fixed upon respective parts of said shaft and having pins in their peripheries, and a plurality of bars de- 115 tachably fixed to said end members and adapted to prevent relative longitudinal movement thereof, substantially as described.

6. In a device of the class described, a sup- 120 porting frame and a two part telescoping shaft, in combination with a drum, said drum comprising end members fixed upon respective parts of said shaft and having pins in their peripheries, means for preventing relative rotary movement of the parts of said 125 shaft and the members carried thereby, and means detachably fixed to said end members for preventing relative longitudinal movement thereof, substantially as described.

7. In a device of the class described, a sup- 130

porting frame and a two part telescoping shaft, in combination with a drum, said drum comprising end members detachably fixed upon respective parts of said shaft and having pins in their peripheries, and means for rigidly holding said end members against relative movement, substantially as described.

8. In a device of the class described, a rotary drum comprising end members having a plurality of pins in their peripheries, means

for adjusting said members toward or from each other, and an adjustable support for said drum, substantially as described.

In testimony whereof I have signed my name to this specification in the presence of two subscribing witnesses.

JOHN L. BRAGDON.
